Patented Jan. 7, 1969

213,098

HOSPITAL CART

Mary Loretia Kocon, 1/2 Sacred Heart Hospital, 9th
and Wilson Streets, Chester, Pa. 19013

Filed Apr. 1, 1968, Ser. No. 11,233

Term of patent 14 years

U.S. Cl. D14—3
Int. Cl. D12—02

FIG-1

FIG-2

FIGURE 1 is an isometric view of the hospital cart looking from above and showing one end and one side thereof, and also showing a hinged compartment cover in open position; and

FIGURE 2 is a similar isometric view showing the end and side of the cart opposite to that appearing in FIGURE 1, and further showing said compartment cover in closed position.

I claim:

The ornamental design for a hospital cart, as shown.
